UNITED STATES PATENT OFFICE

170,564

TOY TALKING DEVICE

Frederick J. Bloss, Pasadena, Calif.

Application January 13, 1953, Serial No. 23,113

Term of patent 3½ years

(Cl. D34—15)

To all whom it may concern:

Be it known that I, Frederick J. Bloss, a citizen of the United States of America, residing at Pasadena, Los Angeles county, State of California, have invented a new, original, and ornamental Design for Toy Talking Device, of which the following is a specification, reference being had to the accompanying drawing, forming a part hereof.

Figure 1 is a perspective view of a toy talking device showing my new design;

Figure 2 is a front elevation thereof;

Figure 3 is a rear view thereof; and

Figure 4 is an edge view thereof.

I claim:

The ornamental design for a toy talking device, substantially as shown.

FREDERICK J. BLOSS.
